UNITED STATES PATENT OFFICE.

HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,238,265.

Specification of Letters Patent. Patented Aug. 28, 1917.

Application filed April 15, 1916. Serial No. 91,451.

To all whom it may concern:

Be it known that I, HENRY PETER CLAUSEN, a citizen of the United States, residing at Mount Vernon, in the county of 5 Westchester and State of New York, have invented certain new and useful Improvements in Telephone-Exchange Systems, of which the following is a full, clear, concise, and exact description.

10 This invention relates to telephone exchange systems, and more particularly to circuit arrangements for selectively operable switching devices in automatic telephone exchanges.

15 It is the object of this invention to reduce the number of switching devices necessary for the establishment of connections in exchanges of the above mentioned type.

In automatic telephone systems having a 20 capacity of more than ninety-nine lines, it has been the practice to provide a first selector switch which may be set in accordance with the first set of impulses corresponding to the "hundreds" designation of 25 the called line, in order to select an idle one in the group of trunks leading to a secondary selector or connector. The called subscriber's line may be seized by setting the connector in accordance with two sets of 30 impulses, corresponding to the "tens" and "units" designation of the called line. This arrangement was found the most satisfactory for use in connection with an impulse sender by means of which impulses on the 35 decimal bases may be sent out.

It is the main object of this invention to provide a circuit arrangement under the control of which a single switching device may perform the functions of the above 40 mentioned primary and secondary selector switches.

The drawings represent a preferred embodiment of this invention, only so much being shown of the switches and the circuit 45 arrangements for operating the same as is necessary for a clear understanding of the invention.

A subscriber, located at station 1, desiring to obtain a connection with a station 2, 50 moves his receiver from the switchhook, whereupon his line is extended in the well-known manner by manually or automatically operated means, to a trunk line 3, 4.

A circuit is completed through the windings 55 of a relay 5, the trunk 3, 4 and the calling

substation for energizing this relay, which in turn causes the energization of a slow-acting relay 6. The calling subscriber now operates his calling device 17 for sending out the first set of impulses. In response to 60 each impulse sent out by the calling subscriber, relay 5 releases its armature once. Relay 6, being slow to release, will not fall off during the vibration of the armature of relay 5, and therefore, in response to the 65 first impulse, a circuit is closed for a slow-acting relay 7, which in turn causes the energization of a side switch magnet 8. The side switch wipers, however, are moved only upon the deenergization of magnet 8. A 70 circuit is also closed from ground through the armature and back contact of relay 5, the armature and front contact of relay 6, a side switch wiper 9 and a vertical magnet 10 to grounded battery. The vertical mag- 75 net is thus operated under the control of relay 5 and steps brushes 11 of a connector 12 in a vertical direction. After the termination of the first set of impulses, relay 5 holds its armature attracted, thus maintain- 80 ing the circuit of relay 6, but opening the circuit of relay 7 for a sufficient length of time to permit the retraction of this relay, whereupon the side switch magnet 8 be- 85 comes deenergized and moves the side switch wipers into their second position.

The next series of impulses will again be received by the vertical magnet 10, due to the fact that in both the first and second positions of the side switch, wiper 9 connects 90 the back contact of relay 5 to this magnet. After the termination of the second series of impulses the side switch is moved into the third position in the same manner as above described, in which position the tens im- 95 pulses will be sent through side switch wiper 9 to rotary magnet 13. Under the control of this magnet the wipers 11 are moved in a rotary direction. The same rotary magnet receives in the fourth position of the side 100 switch the units impulses for selecting the called subscriber's line. In this position ringing current is applied to the called line through side switch wipers 14 and 15, and the side switch wipers are moved into their 105 fifth position in the manner disclosed in Patent No. 1,189,458 to A. E. Lundell, in response to the removal of the receiver at the called station. The calling subscriber will be supplied with battery through the windings of 110

relay 5, and the called subscriber through the windings of a relay 16.

The release of the switches may proceed in the manner disclosed in the mentioned 5 patent to A. E. Lundell.

Obviously the present invention is applicable to selector switches of widely varying character, and may be advantageously used in connection with selector switches having 10 one motion to select a group under the directive control of a subscriber or operator, and a secondary motion for automatically selecting an idle trunk in the selected group.

If the called line terminals are located in 15 the fifteenth rotary and eleventh vertical level of the connector bank, the connector may be set onto these terminals under the control of eight and seven vertical, and six and five rotary impulses. The capacity of 20 the connector bank and the number of switches employed in building up a connection depends on the size of the exchange. In order to permit the seizure of terminals located in the first rotary and vertical levels 25 by sending out two sets, vertical and rotary, of impulses, these first levels are made accessible only in response to two sets of impulses, that is to say, a subscriber's line located in the first rotary level of the first vertical level may be reached by sending out 30 twice one vertical and twice one rotary impulse.

What is claimed is:

1. In a telephone exchange system, a plurality of lines, a selector switch for interconnecting two of said lines, an impulse 35

sending mechanism, and means for operating said selector switch in accordance with more than three complete operations of said mechanism for causing it to establish the 40 desired connection.

2. In a telephone exchange system, a plurality of lines, a selector switch for interconnecting two of said lines, an impulse sending mechanism, and means for moving said 45 switch in two planes in accordance with more than three complete operations of said mechanism to establish the desired connection.

3. In a telephone exchange system, a plurality of lines, a selector switch for interconnecting two of said lines, an impulse sending mechanism, a primary and a secondary magnet for operating said selector switch, and means for operating each of said 55 magnets in accordance with two complete operations of said mechanism.

4. In a telephone exchange system, a selector switch comprising movable and stationary contacts, incoming lines terminating 60 in said movable and outgoing lines terminating in said stationary contacts, an impulse sending mechanism for controlling said movable contacts, and means associated with said selector switch for permitting the 65 setting of said movable contacts in accordance with more than three complete operations of said mechanism for causing the seizure of the desired stationary contacts.

In witness whereof, I hereunto subscribe 70 my name this 14th day of April, A. D. 1916.

HENRY P. CLAUSEN.
